WAVE DRIVEN PRIME MOVER

Isadore Ruderman, San Francisco, Calif.

Application June 11, 1938, Serial No. 213,246

3 Claims. (Cl. 253—12)

This invention relates to a wave driven prime mover.

An object of the invention is to provide a mechanism whereby the ebb and tide of the waves or swells, or any force of a moving body of water in alternate directions can be utilized to an efficient degree for driving a prime mover; the resultant motion being continuously and evenly transmitted to driven mechanism, such as for the direct drive of machinery, or to electric generators and the like.

Another object of this invention is to provide a mechanism in which reciprocating motion is imparted to an impact receiving element by the impact and flow or alternate swell of waves and the like, the said impact receiving elements being guided so as to move on a path converging toward the bottom of the body of water at about an angle corresponding to the average change of depth of the body of water so as to continuously receive the full forces of the waves, means being provided to convert the reciprocating motion of this impact receiving element to a rotary motion of a mechanism for the driving of machines, such as electric generators and the like.

A further object of this invention is to provide a wave driven mechanism which is adapted to be used in multiple units side by side in any suitable number along the beach of a body of water so as to be driven by the movement of the waves in alternate opposite directions; said units being so connected to a common driven mechanism as to impart rotary movement to a drive shaft in the same direction without interference of one unit with the operation of the other units.

I am aware that some changes may be made in the general arrangements and combinations of the several devices and parts, as well as in the details of the construction thereof within the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description and specifically pointed out in the appended claims, reference is had to the accompanying drawings for the illustrative embodiment of the invention, wherein:

Fig. 1 is a fragmental sectional side view of a wave driven mechanism constructed in accord-

ance with my invention, the section being taken substantially on lines 1—1 of Fig. 2.

Fig. 2 is a fragmental, front view of my wave driven mechanism, partly in section.

Fig. 3 is a fragmental sectional view of a suspension head for the impact receiving element.

Fig. 4 is a fragmental sectional view of an illustrative drive transmission of my device.

Fig. 5 is a fragmental view of a modified form 10 of my wave driven mechanism.

Fig. 6 is a sectional view, taken on lines 6—6 of Fig. 7.

Fig. 7 is a sectional view, taken on lines 7—7 of Fig. 5, and

Fig. 8 is a sectional view taken on lines 8—8 of Fig. 7.

In its general organization my device includes a plurality of cooperating units, each unit being constructed in the same manner but in conformance with the respective shore or beach conditions immediately at the respective units. All the units are connected to a common driven mechanism and work on the same continuously. All these units are side by side along a suitable 20 length of the shore or beach and preferably follow the shore line. Each unit extends into the water oppositely to the waves and each unit works on a plurality of driven mechanisms to be operated successively at different strokes created 30 by the varying height and nature of the swells or waves. The stroke in each unit is on a path substantially convergent with the bottom of the beach toward the shore at a degree about corresponding with the average gradual shallowing of 35 the waves as they usually spread toward the shore.

In carrying out my invention I make use of a frame work 7 which extends from the shore into the body of water preferably to a point about 40 where the outermost breaker line occurs normally. The frame work 7 has parallel channels 8 which have their open slots 9 pointing toward each other in pairs. These channels 8 are arranged at the aforesaid converging angle relatively to the sea or lake bottom. In each facing pair of channels 8 is guided a floating vane 11 by means of grooved wheels 12 which latter are run on triangular tracks 13 longitudinally in the channels 8. The wheels 12 are journaled on stub 50 shafts 14, one extended from each end of the floating vane 11 through the adjacent slot 9 and into the channel 8. Each vane 11 is preferably made of a steel or other hard casing or jacket which incloses a hollow space filled with a light 55 and buoyant material such as cork filling 16.

Each vane 11 is so proportioned as to present a comparatively large surface preferably its largest surface, in the path of the waves substantially at right angles to the sea bottom thereat.

Each vane 11 is guided and suspended on upwardly extended arms 17 each of which has a suspension head 18 on the top slidably held in upper rails 19 which latter are inside of and above but are parallel with the channels 8. In order to prevent binding and reduce friction a suitable number of rollers 21 are mounted on each head, distributed both forwardly and rearwardly of the arms 17 to take up the torque with minimum friction in either direction. The rollers 21 are substantially parallel with the vane 11 and are located both under and above the transverse suspension head 18. The upper rails 19 are connected to each other at suitable intervals by substantial cross braces 22 and are supported by substantial columns 23 on the frame 7. Thus substantially true alignment of the vane 11 is assured when moved by the action of the waves.

Along the top rails 19 are journalled aligned gear-wheels 24. A gear-rack 26 is mounted on the top of the vane 11 near one of the channels 8 and is guided by roller guides 27 on the top of the adjacent channel 8 so as to travel parallel with the channel 8 as the vane 11 is reciprocated by wave action. The gear-rack 26 is aligned with the row of gear-wheels 24 and is preferably of such length as to rotate at least two successive gear-wheels 24 at all times as it is carried along successively from gear-wheel 24 to gear-wheel 24 by the vane 11.

The rotation of the gear-wheels 24 may be transmitted in any suitable manner so as to be converted from intermittent alternately opposite movement into a substantially continuous one way rotation. For instance in the herein illustration there is extended a continuous driven shaft 28 above and parallel with the shaft of each gear-wheel 24. This driven shaft 28 is journalled in brackets 29 suitably extended from the frame 7 so as to support the driven shaft 28 along all the units. It is to be noted that the rows of gear-wheels 24 of each unit are so arranged and spaced that the gear-wheels 24 of the adjacent units are also aligned transversely below the same driven shaft 28.

There is a transmission on the driven shaft 28 opposite each gear wheel 24. The transmissions may include any suitable clutches, or transmission or differential mechanisms and they may be so made as to either transmit power from the shore-ward stroke of the vane 11, or to transmit power also during the return stroke of the vane 11. Rotation of the driven shaft 28 is then transmitted by suitable transmission such as the belt transmission 30 to a machine or electric generator or the like mechanism, not shown, where the same is put to useful application.

In the herein illustrative embodiment each gear wheel 24 is in mesh with a gear 31 on the shaft 28. A hub 32 of the gear 31 has a spring pressed ratchet pawl 33 to engage a ratchet wheel 34 which latter is keyed to the driven shaft 28. When the vane 11 is moved by the waves toward the shore then the gear 31 is rotated in a contra-clockwise direction, viewing Fig. 4, and thus transmits rotation to the driven shaft 28. On the other hand upon the return or rearward stroke of the vane 11 the pawl 33 slides over the ratchet wheel 34 without engaging the same.

In the embodiment of the devices shown in Figures 5 to 8, I illustrate a manner in which the

return stroke of the vane 11 may be also utilized for power purposes. This arrangement is particularly necessary in instances where the return movement of the vane 11 as caused by its gravity and by suction of the waves develops sufficient force to be utilized. In this form of my device another hollow hub 36 is extended from the gear 31 oppositely to the first hollow hub 32. In this hollow hub 36 is a spring pressed pawl 37 for engaging a toothed ratchet wheel 38 on a sleeve or tube 39 which extends from a gear wheel 41 journalled on antifriction bearings 42 on the driven shaft 28. The pawl 37 and ratchet wheel 38 catch oppositely to the first pawl 33 and ratchet wheel 34, so that the second or reverse pawl 37 and ratchet wheel 38 are in driving connection during the return movement of the vane 11 and idle or slide during the shore-ward movement of the vane 11.

This last described reverse movement may be transmitted separately but it is preferable to transmit the same to the same driven shaft 28. For this purpose the gear wheel 41 is provided with internal gear teeth 43. From the fixed shaft bearing bracket 29 are extended diametrically opposite arms 44 outwardly and toward the gear wheel 41 and on the ends of each arm 44 is journalled an idler gear 46 in mesh with the internal gear teeth 43. The idler gears 46 are also in mesh with a central gear 47 which latter carries a pawl 48 for engagement with a ratchet wheel 49 keyed to the driven shaft 28, so as to transmit rotation in the same direction as the first pawl 33 and ratchet wheel 34. Thus the reverse rotation caused by the return movement of the vane 11 is converted into rotative force in the same direction as the direct rotation of the driven shaft 28.

In operation the waves or swells strike the vane 11 and push it along between the channels 8 while the rails 9 and suspension heads 18 and rollers 21 hold the vane 11 in position in the path of the wave throughout its stroke. During the reciprocation of the vane 11 the gear rack 26 rotates successively as many gear-wheels 24 as it comes in contact with depending on the length of the wave or swell or breaker. The rotation is transmitted in the aforescribed manner from each gear-wheel 24 to the driven shafts 28 which latter transmit it to the respective belt transmission 32 by which latter in turn the power and rotation is transmitted where the same is to be utilized. Each row of aligned gear-wheels 24 of the series of units works on the same driven shaft 28, so that the cumulative action of the series of vanes 11 is imparted for continuous operation regardless of the variations in the length or regularity of the wave motion. The prime mover herein described can be arranged flatly and used on shallow beaches and shores even where the tides are usually low, and it is flexible so as to be readily adaptable to the contour of the sea or water bottom and of the shore line. It can be made up in units suitable for the desired power to be developed. The entire device can be covered or housed if so desired and is easily adaptable to the large variety of existing local conditions and requirements.

I claim:

1. In combination, a frame, parallel guides thereon extended along the bottom of a body of water at an angle to the direction of the horizontal plane of the wave and convergent with the bottom toward shore, a vane positioned on said guides so as to receive the impact of the waves and be reciprocated along said guides by the

waves, means of connection between said vane and said guides to confine the path of vane movement to reciprocation at a constant angle relatively to the bottom of the body of water, and means to convert and transmit the motion of the vane.

2. In combination, a frame, parallel guides thereon extended along the bottom of a body of water at an angle to the direction of the horizontal plane of the wave and convergent with the bottom toward shore, a vane positioned on said guides so as to receive the impact of the waves and be reciprocated along said guides by the waves, means to convert and transmit the motion of the vane, means of connection between said vane and said guides to confine the path of vane movement to reciprocation at a

constant angle relatively to the bottom of the body of water, and means of connection between the guides and the vane to hold the vane at a constant angle relatively to said guides.

- 5 3. In combination, a frame, parallel guides thereon extended along the bottom of a body of water at an angle to the direction of the horizontal plane of the wave, a vane positioned on said guides so as to receive the impact of the waves and be reciprocated along said guides by the waves, means to convert and transmit the motion of the vane, overhead suspension means for the vane for reciprocable suspending the vane, and means connected to said suspension means to 10 prevent the twisting of said vane from the path of the wave.
